CLAIM

The ornamental design for a high heel accessory, as shown and described.

DESCRIPTION

FIG. 1 is a perspective view from above of the high heel accessory;

FIG. 2 is a back elevational view thereof;

FIG. 3 is a front elevational view thereof;

FIG. 4 is a side elevational view thereof, the opposite side being a mirror image;

FIG. 5 is a top plan view thereof; and,

FIG. 6 is a bottom plan view thereof.

The features shown in broken lines in FIGS. 1, 5 and 6 form no part of the invention.
